DESIGN FOR A COMBINED CONTAINER CUP AND SLEEVE FOR ELECTRICAL VAPOR- IZER

Joseph Robinson, New York, N. Y.

Application October 26, 1935, Serial No. 59,233

Term of patent 14 years

To all whom it may concern:

Be it known that I, Joseph Robinson, a citizen of the United States, residing at New York, in the county of New York and State of New York, have invented a new, original, and ornamental Design for a Combined Container Cup and Sleeve for Electrical Vaporizer, of which the following is a specification, reference being had to the accompanying drawing, forming a part thereof, in which—

Figure 1 is a side elevational view of a com-

bined container cup and sleeve for electrical vaporizers showing my new design;

Figure 2 is a top plan view thereof;

Figure 3 is a bottom plan view thereof, and

Figure 4 is a vertical cross-sectional view on the line 4—4 of Figure 1.

I claim:

The ornamental design for a combined container cup and sleeve for electrical vaporizer, substantially as shown.

JOSEPH ROBINSON.
